UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC SELECTOR-SWITCH.

1,363,365.

Specification of Letters Patent. Patented Dec. 28, 1920.

Application filed November 5, 1917. Serial No. 200,318.

To all whom it may concern:

Be it known that I, FRANK M. SLOUGH, a citizen of the United States, and residing at Rochester, in the county of Monroe and 5 State of New York, have invented certain new and useful Improvements in Automatic Selector-Switches, of which the following is a full, clear, concise, and exact description.

This invention relates to a telephone 10 switch, and is particularly designed for use as a line switch, or trunk finder switch, although obviously it may be used for many other purposes.

The invention particularly relates to a 15 switch of the cross-bar type in which groups of intersecting bars are provided, and whereby the conjoint action of a bar of one group with that of another group is arranged to cause inter-engagement between 20 sets of terminal contacts, the same being in the form of contact springs mounted in a bank.

One of the objects of my invention is the 25 provision of a simple switch structure of the above type, by means of which the connection of lines will be accomplished with rapidity and certainty, and wherein the parts will be readily maintained in their adjusted positions.

Another object is the provision of a structure of this kind which can be cheaply manufactured and inexpensively maintained in 30 operation.

Another object is to make the aforesaid 35 connections in such a way that the electrical contacts will be accompanied by a wiping of the contact surfaces that they may be kept clean.

Other objects and advantages will appear 40 as the description of the invention progresses.

In order to facilitate the explanation and 45 understanding of this invention, it will now be described as a line switch or trunk finder, and as such, might be arranged to serve, for example, a group of 100 subscribers' lines and a corresponding group of trunk lines, ordinarily less in number, and commonly of from 10 to 20% of the number of subscribers' lines. It is, of course, obvious that in 50 the following description, the terms "incoming lines" and "outgoing lines" might be substituted for lines or subscribers' lines, and trunk lines, respectively.

The embodiment of the apparatus herein 55 disclosed comprises two sets of longitudinally movable bars or shafts and means whereby the said bars may be longitudinally displaced to release, what I call a plug carriage at the intersection of the displaced 60 line and trunk bars.

The plug carriage referred to contains insulated metallic plugs carried at one extremity thereof, each adapted to plunge when the plug carriage is released between a pair 65 of jack springs mounted in an insulating bank.

For a more complete description of the device, reference is now made to the drawings in which Figure 1, shows an isometric 70 view of the switch with parts broken away for the sake of exposing other operative parts. Only three plug carriages are shown in Fig. 1, the others being merely indicated in various ways; but it will be understood 75 that the other plug carriages not shown are like the illustrated plug carriages and operated in the same way.

Fig. 2 shows a plan and elevation of one 80 of such plug carriages, together with certain associated parts which control the operation of the plug carriage. The plug carriage illustrated in Fig. 2, is shown partly in section for the sake of a better understanding of the construction of the same.

Fig. 3 shows a plan and elevation illustrating such a plug carriage and associated 85 controlling elements when not in their fully operated position.

Fig. 4 shows a plan and elevation illustrating such a plug carriage and associated elements in the position which they would assume when another plug carriage in the same vertical row has been previously operated, such as the plug carriage of Fig. 3, the 90 plug carriage of Fig. 4 being shown in its unoperated barred condition, that is, in the condition wherein it is prevented from operating by the previous operation of the other plug carriage in the same vertical row, as 100 for instance, the plug carriage of Fig. 3.

Referring now to the figures in all of 105 which like reference numerals are used to designate like parts, and referring particularly to Fig. 1 reference being, however, also had to the other figures for the sake of better understanding the disclosure of Fig. 1; at AR and BR, I show horizontal line bars,

each individual to a different subscriber's line, each capable of being longitudinally displaced by line magnets AM and BM, respectively, each magnet being individual to its associated subscriber's line. The magnets displace the line bars against the power of the springs LS, which control the operation of associated electrical contacts.

Trunk bars D and E are shown arranged at right angles to the line bars and are adapted to be longitudinally displaced against the power of the spring TS by electromagnets DM and EM, each trunk bar and each trunk electromagnet being individual to a given trunk, or outgoing line. Plug carriages AC and AP, BC and BP are arranged at the intersection of the line and trunk bars. By the conjoint action of a line bar, such as AR, and a trunk bar, such as D, the plug carriage AC adjacent to the intersection thereof will be released, and will under the propelling action of the spring PS plunge the plug contacts 2, 3 and 4, between the jack springs 5 and 6, 7 and 8, and 9 and 10, to interconnect the line springs 5, 7 and 9 of a set of springs to the trunk springs 6, 7 and 10 of the set of springs. The plugs 2, 3 and 4 are each mounted in an insulating block Y, each plug being insulated from the other and having no terminal wires connected thereto. The jack springs are mounted in a bank to coöperate with the plugs above mentioned. Like springs in the same vertical row are shown connected in multiple, and like line springs in the same horizontal row are also shown connected in multiple. Like trunk jack springs in the same vertical row are preferably stamped from a single sheet of metal, in which case the multiple connection between these jack springs is taken care of without additional connecting wires. The multiple connections between the line jack springs would be taken care of by means of conducting wires, such as CW.

The release of the plug carriage in the embodiment of my invention illustrated in the drawings is accomplished in the following way:—

At AP in Figs. 1 and 2, I show the plug carriage in its normal or unoperated position. At AK, I show key-pins carried by the line bar AR, and which normally rest in the extension z of the slot Z. As shown in Fig. 1, however, the line bar AR is shown displaced from normal position to its operative position by the energization of the line electromagnet AM, as for instance, due to the subscriber taking his receiver from the hook. Therefore, instead of the key pin AK locking the line bars of the calling line, the key pins of this line bar unlock all of the plug carriages, as for instance, AC and AP associated with the calling line. If the line bar were not operated, the key pins AK rest-

ing in the extension z of the slots Z would prevent these plug carriages, AC and AP, from operating. The plug carriage is now prevented from operating by the turned edge of the slot in the plug carriage resting against the side of the extension y of the collar C. This collar is securely fastened to the trunk bar E, and is constructed with an extended portion y for the above purpose and other purposes to be described. 75

Now, in the switch of my invention, the line bar having operated, a subsequent operation of a trunk bar, such as the trunk bar D, will complete the unlocking of the plug carriage, and the plug carriage will 80 then be propelled by its propelling springs PS to a position wherein the plug contacts 2, 3 and 4 will engage the jack springs 5, 6, 7, 8, 9 and 10, as before mentioned. Such an operated plug carriage is shown at AC. 85 After the operation of this plug carriage the circuit of the line magnet AM will be opened, and the spring LS will thereupon restore the line bar AR to its normal position, restoring the key pin AK of the unoperated plug carriages associated with the line of the slot extensions Z thereof, thus locking these plug carriages in their unoperated positions, but in the case of the key pin AK associated with the operated plug carriage, this will now come to rest at the point w of the slot Z. 90

The V shaped turned edge of the slot in the plug carriage T now is projected between the box like extension y of the collar C 100 mounted on the trunk rod and the box like collar N which is slidably mounted on the trunk rod. This member N, is capable of being lifted a certain distance on the trunk rod D against the power of the coiled spring 105 S. Therefore, the trunk rod being longitudinally displaced by the trunk magnet DM and the V shaped edge, projecting under this box-like yieldingly secured collar, and the downward motion of the trunk rod continuing, the box like collar N will be held stationary, while the motion of its carrying rod D continues. Finally the trunk rod D and the collar associated therewith attains the position shown in the drawings of Fig. 110 3, which shows a plan and elevation of such a fully operated plug carriage. 115

The plug carriage BC is located in the same vertical row as the plug carriage AC and is served by the same trunk rod D. 120 When the trunk rod D was depressed, the plug carriage BC, however, maintained its unoperated position due to the fact that the key pin AK of line bar BR associated with this plug carriage prevented the movement 125 thereof, since this line bar belonging to a different line was not operated and the key pin AK rested within the extension z of the slot Z, in the plug carriage BC.

The parts referred to, namely, the slot Z 130

and key pin AK, are not capable of being seen in the view shown in Fig. 1, due to their being hidden by the plug carriage AP. Such a plug carriage is illustrated in detail 5 in the views of Fig. 4, showing a plan and elevation of such a barred plug carriage.

The plug carriage BC being held therefore, during the operation of the trunk bar by its key pin AK, is thereafter prevented 10 from operating by the turned edge of the plug carriage, engaging the side n of the yieldingly secured box like structure N which is associated with this plug carriage, that is, the other unoperated plug carriages 15 in the same vertical row as an operated plug carriage will be thus thereafter during the connection period prevented from operating, even though other line bars may thereafter be operated in response to a subsequent call 20 over other associated subscribers' lines. This is to prevent two lines being connected to the same trunk after the trunk has been connected to one of the lines.

When used as a line switch, I prefer to 25 operate the switch of my invention in such a manner that a subscriber in making a call will first displace his line bar by energizing his line magnet, and thereafter by means of associated electrical circuits a trunk bar of 30 an idle trunk will be operated to cause the said line wires terminating in jack springs to be interconnected to the trunk wires likewise connected to jack springs.

The operation of the line bar will pref- 35 erably continue only until the proper plug carriage has been operated, it thereafter re- turning to its normal position. The trunk bar on the contrary I cause to be held in its operated position for the full conversational 40 period.

Assuming now that the plug carriage, such as AC, having been operated to cause a connection to be established, it is desired to terminate this connection, the same will 45 be accomplished by deenergizing the mag- net DM which will thereupon release the vertical trunk rod D, and the same will be propelled upward to its normal position by the power of the spring TS. In the upward 50 motion of the rod D the operated plug carriage AC will be propelled back to its nor- mal position by the extension Y of the col- lator C of the trunk rod exerting a cam ac- 55 tion on the inclined side of the V shaped ex- tension K of the plug carriage, thus pro- pelling the plug carriage so that the plugs 2, 3 and 4 are removed from engagement with the jack springs; the pin AK of the line bar will ride on the inclined surface k 60 of the slot Z of the plug carriage causing a momentary motion of the line bar AR to its fully operated position, and then the pin AK drops into the recess z of the slot Z, which is its normal unoperated position. 65 The above restoring action presupposes a

proper proportioning of the various springs involved.

Sets of springs are shown at J, associated with each of the trunk bars and operate to open and close electrical contacts whenever 70 the trunk bars are operated. These perform functions in the operation of the circuits involved in the use of this switch. Like sets of spring contacts are shown at L, for the line bars for similar purposes. 75

Although I have described the switch of my invention as being operated in a certain way, it is obvious it may be operated in various other ways and which are contemplated in this disclosure. And it is under- 80 stood that other numerous and extensive de- partures may be made from the same without departing from the spirit of my invention, but what I claim as my invention is de- fined in the following claims: 85

1. In a telephone switch, the combination of two sets of bars, the bars of one set being disposed at an angle to the bars of the second set, a pair of contact springs, a panel bank, the said pair of contact springs being 90 rigidly mounted in the said panel bank, a plug carriage, a metallic plug in said carriage, and means independent of said sets of bars to cause the said plug carriage to convey the said plug to a position between 95 the said springs, to interconnect the said springs, the said means being conditioned to operate by the conjoint operation of a bar of each set.

2. In a telephone switch, the combination of two sets of bars, the bars of one set being disposed at an angle to the bars of the second set, a pair of contact springs arranged in a panel adjacent to each intersection of the bars of the two sets, a plug carriage for each 100 pair of contact springs carrying a metallic plug, and a spring to move the said plug carriage to convey the said plug to intercon- 105 nect the said springs, the said springs being conditioned to operate by the conjoint op- eration of a bar of each set. 110

3. In a telephone switch, the combination of two sets of bars, the bars of one set being vertically mounted and the bars of the sec- 115 ond set horizontally mounted, a pair of con- tact springs, a panel bank, the said pair of contact springs being rigidly mounted in the said panel bank, a plug carriage carrying a metallic plug mounted adjacent to the said pair of contact springs, but normally 120 out of contact therewith, and propelling means independent of said sets of bars con- ditioned to operate by the conjoint operation of a bar of each set to convey the said plug to a spring interconnecting position. 125

4. In a telephone switch, the combination of a set of horizontal and a set of vertical bars, the horizontal bars being capable of momentary operation and the vertical bars being capable of continuous operation, a 130

pair of contact springs mounted in an insulated panel bank, a plug carriage carrying a metallic plug arranged in proximity to the said contact springs, and propelling means to propel the said plug carriage to a spring operating position, the said propelling means being conditioned to operate by the conjoint operation of a bar of each set, and controlling means for the vertical bar 10 of the set to cause the said vertical bar to thereafter hold the said plug carriage in its operated position.

5. In a telephone switch, the combination of a set of horizontal and a set of vertical bars, plug carriages mounted in a frame adjacent the intersections of the said bars, a panel bank, flexible contact springs mounted therein, a pair of the said contact springs being arranged in proximity to each 15 of the said plug carriages, relatively rigid insulated metallic plugs carried by each of the said plug carriages, and adapted when the same are operated to interconnect the associated pair of contact springs, and propelling means for each of the said plug carriages conditioned to operate the same by the conjoint momentary operation of a bar of each set, one of the operated bars being adapted to maintain an operated plug carriage in its operated position when in its operated position, and to restore the said plug carriage when the said bar is restored to its 20 normal position.

6. In a telephone switch, the combination 35 with an insulating jack panel therefor, a plurality of sets of flexible jack springs mounted rigidly in the said panel, a plurality of plug carriages for the said switch, each carrying rigid metallic plugs, propelling means individual to each of the plug carriages, two sets of controlling bars, the bars of one set being disposed at an angle to the bars of the second set, the conjoint operation of a bar of each set conditioning the 40 said propelling means to operate the said plug carriage, to plunge the said plugs between the jack springs of a set arranged in proximity thereto, to interconnect the contacting springs.

50 7. In a telephone switch, the combination with a plurality of flexible contact springs arranged in pairs, a spring propelled switching member for each pair, a group of longitudinally movable bars, a second group 55 of bars arranged at right angles to the first group of bars, and an interlocking mechanism between the said switching member and a bar of each group to maintain the said switching member in its normal position, and when said bars are operated to release the said switch member to operate the associated pair of contact springs.

8. In a telephone switch, the combination 65 of sets of intersecting bars, contact sets at the intersections of the said bars, operat-

ing members adjacent to the said contact sets, unlocking members carried by a bar of one of the sets to conditionally unlock all the associated operating members, an unlocking member for an intersecting bar of 70 the other set to completely unlock a commonly associated operating member, and means individual to the said operating member to cause it to thereupon operate the adjacent contact set. 75

9. In a telephone switch, the combination of sets of intersecting bars, contact sets at the intersections of the said bars, an operating member adjacent to each of the said contact sets, an unlocking member carried by a bar of one of the sets to conditionally unlock its associated operating members, an unlocking member carried by a bar of the other set to complete the unlocking of a commonly associated operating member, 85 means individual to the said operating member to cause it to thereupon operate the adjacent contact set, and an additional locking member carried by the last-named bar to lock all other associated operating members, not common to both operated bars. 90

10. In a telephone switch, the combination of sets of intersecting longitudinally displaceable bars, contact springs adjacent and individual to said bars, respectively, 95 plugs arranged for rectilinear movement at the intersections of the said bars to cause interconnection of the contact springs individual to the one set of bars to the springs individual to the other set of bars whereby the 100 successive operation of a bar of each set in a definite order only will permit the actuation of the plug at the intersection of the bars.

11. In a telephone switch, the combination 105 with a plurality of displaceable bars divided into two groups, the bars of one group being arranged at an angle to the bars of the second group, a plug and jack switch associated with each bar intersection, and means arranged for rectilinear movement whereby the actuation of a bar of each group in a definite order only will selectively operate plug and jack switch contacts remote from the intersection of the said 110 bars. 115

12. In a telephone switch, the combination 120 of sets of intersecting bars, contact sets at the intersections of the said bars, a plug operating member adjacent to the said contact sets, an unlocking member carried by a bar of one set to conditionally unlock the operating member, an unlocking member carried by a bar of the other set to complete the unlocking of a commonly associated operating member, means individual to the said operating member to cause it to thereupon operate the adjacent contact set, and an additional locking member flexibly secured to the last-named bar to lock all other 125 130

operating members associated with the last-named bar.

13. In a telephone switch, the combination of sets of intersecting bars, contact sets at the intersections of the said bars, a contact operating member adjacent to the said contact sets, an unlocking member carried by a bar of one of the sets to conditionally unlock the operating member, an unlocking member carried by a bar of the other set to complete the unlocking of a commonly associated operating member, means individual to the said operating member to cause it to thereupon operate the adjacent contact set, 10 an additional locking member flexibly secured to the last-named bar to lock all other operating members associated with the last-named bar, and a locking member flexibly secured to the last-named bar to lock an unconditioned associated operating member.

14. In a telephone switch, the combination of sets of intersecting bars, contact sets at the intersections of the said bars, a contact operating member adjacent to the said contact sets, an unlocking member carried by a bar of one of the sets to conditionally unlock the operating member, an unlocking member carried by a bar of the other set to complete the unlocking of a commonly associated operating member, means individual to the said operating member to cause it to thereupon operate the adjacent contact set, an additional locking member flexibly secured to the last-named bar to lock an associated unconditioned operating member, the unlocking member of the last-named bar being adapted to engage the said operating member to restore the same to its normal position when the last-named bar is restored 40 to normal.

15. In a telephone switch, the combination with a plurality of displaceable bars, arranged in two groups, the bars of the second group being arranged at an angle to the bars of the first group, contact sets arranged at the intersections of the bars, an operating member for each of the contact sets adapted to operate by the conjoint displacement of a bar of each set, the said operating member operating without partaking of the motion of either of the said bars, and, being restored to normal independent of the position of the bar of one set under the sole control of the bar of the other set.

16. In a telephone switch, the combination with a plurality of displaceable bars arranged in a group, a second group of displaceable bars arranged at an angle to the bars of the first group, contact sets arranged at the intersections of the bars, an operating member for each of the contact sets adapted to operate by the conjoint displacement of a bar of each set, the said operating member operating without partaking of the motion of either of the said bars, and, being restored

to normal independent of the position of the bar of one set under the sole control of the bar of the other set.

17. In a telephone switch, the combination with a plurality of displaceable bars 70 divided into two groups, the bars of one group being arranged at an angle to the bars of the second group, and means whereby the actuation of a plurality of bars of one group and a successive actuation of a bar of the 75 second group will operate plug and jack switches at the intersections of the said bars.

18. In a telephone switching mechanism, the combination with a terminal bank, of a plurality of sets of contact terminals arranged in horizontal rows, a plurality of rows of contact terminals of another group arranged at right angles to the rows of the first group, the last-named terminals comprising extensions of unitary metallic strips, 80 the terminals of the one group being arranged adjacent to terminals of the second group, a plurality of displaceable bars arranged in a group, a second group of displaceable bars arranged at an angle to the 90 bars of the first group, each of the said bars corresponding to an associated row of contact terminals, and an operating member for each set of the adjacent terminals comprising terminals of the two groups, the said 95 operating member being adapted to operate by the conjoint displacement of a bar of each set, to interconnect adjacent terminals of said set.

19. In combination, non - self - restoring- 100 switching devices, movable bars, operating links controlled by the common operation of said bars to actuate said switching devices, electromagnetic means for each of the bars adapted on energization to operate the 105 said bars, and restoring means for each of the said switching devices operative upon deenergization of an associated bar electromagnetic means.

20. In combination, non - self - restoring- 110 switching devices, movable bars, operating links controlled by joint operation of said bars to move said switching devices to closed circuit position, and means for actuating one of said movable bars, to restore 115 the said movable bar and the switching device operated thereby to normal or open circuit position.

21. In combination, switching devices 120 which are not self-restoring, movable bars, operating links controlled by joint operation of said bars, to move said switching devices from their normal position, electromagnetic means for moving one of said movable bars, and restoring means for said 125 switching devices operative upon the deenergization of said electromagnetic means.

22. In an electrical switch mechanism, the combination of sets of intersecting bars, contact springs adjacent to the intersections 130

- of the said bars, contact spring actuating means therefor, and means whereby the longitudinal displacement of a bar of each set will actuate the spring contact actuating means to cause interconnection between the different springs of a set of contact springs, the said act of interconnection being accompanied by frictional contact of the surfaces of the said contact springs.
23. In a switch of the class described, the combination of a bank of contact sets, each contact set comprising a contact of two different classes, a connection effecting member for each set of contacts adapted by a longitudinal movement to effect connection between the contact of the one class and the contact of the other class of contacts, a movable operating bar for each class of contacts, said connection effecting member being under the conjoint control of both of the said bars.
24. In combination, switching devices, a set of bars movable in one direction, a second set of bars movable in another direction, operating links mounted independently of said switching devices, means under the control of a bar of each set for moving the said operating links by a rectilinear movement to operate the said switching devices.
25. In combination, switching devices, a set of bars movable in one direction, a second set of bars movable in another direction, operating means for each of said sets of bars, operating links mounted independently of said switching devices, said links not partaking of the motion of said sets of bars.
26. In combination, switching devices, a set of bars movable in one direction, a second set of bars movable in another direction, operating means for each of said sets of bars, operating links mounted independently of said switching devices, said links not partaking of the motion of either of said bars.
27. In combination, switching devices, a set of movable bars arranged in one plane, a second set of movable bars arranged in planes intersecting said first plane, movable links forming intersecting sections for said bars of different planes, said links being controlled by conjoint operation of said movable bars, a magnet to operate each of the said bars, propelling means for the said links, said propelling means propelling the said links to actuate said switching devices without partaking of the motion communicated to any of the said bars by the said magnets.
28. In combination, a set of longitudinally movable bars, a second set of longitudinally movable bars, contact terminals remote from the bars of each set, switching devices for connecting said contact terminals, operating links controlled by conjoint operation of a bar of each set to selectively operate one of the said switching devices and propelling means for said links independent of said bars.

In witness whereof I hereunto subscribe my name this 2nd day of November, A. D. 1917.

FRANK M. SLOUGH.
